[57] CLAIM

The ornamental design of a holder for a flagstaff or the like, as shown.

DESCRIPTION

FIG. 1 is a left side elevational view of a holder for a flagstaff or the like showing our new design;

FIG. 2 is a front elevational view thereof;

FIG. 3 is a half sectional side view thereof;

FIG. 4 is a rear elevational view thereof;

FIG. 5 is a top plan view thereof;

FIG. 6 is a right side elevational view thereof;

FIG. 7 is a sectional view as taken from line 7—7 of FIG. 1;

FIG. 8 is a sectional view as taken from line 8—8 of FIG. 1;

FIG. 9 is a bottom plan view thereof.

FIG. 5

FIG. 6

FIG. 7

FIG. 9

FIG. 8
